UNITED STATES PATENT OFFICE.

WALTER THOMAS MOON, OF BALTIMORE, MARYLAND.

BUCKLE HOLDER.

Application filed December 24, 1925. Serial No. 77,530.

The present invention relates to improvements in buckle holders, and more particularly to an improved means for detachably supporting buckles, bows, or other ornaments upon that class of shoes or slippers commonly known as pumps.

The primary object of the invention being to provide an improved buckle holder embodying locking means whereby the buckle 10 may be snapped into locked fixed relation with the holder and there held in a firm and straight position on the pump.

A further object of the invention is to provide an improved buckle holder adapted 15 for detachably holding a buckle, thus permitting of differently ornamented buckles being supported upon the pump.

A still further object of the invention is to provide an improved buckle holder which 20 may be readily supported upon the vamp of the pump without liability of defacing the outer surface of the vamp, and which holder when in position is held against shifting by the instep of the person wearing the pump.

A still further object of the invention is to provide an improved buckle holder which may be readily inserted between the vamp of the shoe and one's instep, in a manner 25 so as not to allow the vamp to press or cut 30 the instep, due to the particular shape of the base portion of the holder which tends to relieve the pressure or binding on the instep.

A still further object of the invention resides in the provision of an improved holder 35 of this character which is extremely simple in construction, and one wherein no separate parts are employed either for attachment of the holder to the shoe nor the buckle 40 to the holder.

Other objects and advantages of the invention will be apparent during the course 45 of the following detailed description, taken in connection with the accompanying drawing forming a part of this specification and in which drawing:

Figure 1 is a perspective view of a pump or slipper and showing an ornamented buckle held in position upon the vamp by 50 the improved holder.

Figure 2 is a perspective view showing a buckle locked in position upon the holder.

Figure 3 is a central vertical section 55 through the holder and buckle and showing the same in adjusted relation upon the vamp of a shoe.

Figure 4 is a transverse section on line 4-4 of Figure 3.

Figure 5 is a horizontal section on line 5-5 of Figure 3; and,

Figure 6 is a view of the improved holder in blank form.

Referring to the drawing in detail, and wherein similar reference characters designate corresponding parts throughout the several views; the letter A may designate a slipper or pump, B a buckle or other suitable ornament for adornment of the pump A, and C the improved holder for detachably supporting the ornament B upon the 70 pump A.

In the example shown, the ornament B is in the form of a buckle comprising a rectangular frame 10 and a vertically extending central cross bar 11 attached at its upper and lower ends to the horizontal portions of the frame 10, and which cross bar preferably extends in slightly spaced relation from the rear face of the frame. It is of course understood that the cross or supporting bar 11 80 may form the attaching section of any desired ornament, and that if so desired ribbons or other articles of ornamentation may be carried by the frame 10.

The improved holder C which may be 85 stamped from sheet metal of a suitable gauge and preferably of a spring nature, embodies an upstanding body portion 12 having a forwardly bent base portion 13. The base portion 13 which is preferably of greater width 90 than the upstanding portion 12, is divided by a forwardly opening slot 19 into a pair of feet or rest plates 14 preferably rounded at their forward ends as at 15. The forwardly opening slot 19, as will be readily seen 95 from Figure 3, preferably has its rear end extending upwardly for a slight distance into the lower portion of the upstanding body portion 12.

The object in so extending the base of the slot 19 for a slight distance up into the body portion 12, is to permit of free yielding of one rest plate 14 with respect to the other. Struck upwardly from points adjacent the forward end of the rest plate 14, are fangs or teeth 16 having their pointed free ends extending rearwardly toward the body portion 12. While the fangs 16 have been shown as being struck upwardly from the plates 14, it will be apparent that other suitable teeth may be provided on the upper 110 faces of the plates, the method illustrated for forming the fangs merely being shown as a

preferred method. The base portion 13 is preferably arcuated slightly transversely of the holder in order that the plates 14 will rest flat upon the instep, and also conform to the arcuate contour of the vamp of the pump.

At the base or juncture of the upstanding body portion 12 with the base portion 13, the holder is slightly arcuated as at 17 for conforming to the upper edge of the vamp 18 and which arcuation forms a groove extending transversely of the base of the body portion 12 for receiving the upper edge of the vamp.

15 Struck forwardly from the lower portion of the upstanding body portion 12, and transversely of the body portion, is a spring tongue 20 preferably formed with a pointed or V shaped free end 21. As will be seen 20 from Figure 2, the spring tongue 20 extends to each side of the vertical center of the body portion 12, that is, the point of connection with the tongue to the body portion is to one side of the vertical center of the body portion 12 while the pointed free end of the tongue is to the opposite side of the vertical center of the body portion. A transversely extending slot or opening 22 is formed in the upper portion of the body 12, 25 as by cutting or punching out a portion of the material below the top edge of the body, and which slot is spaced above the tongue 20 for leaving a transverse medial web or rib 23 directly above the tongue. The retained portion of the body 12 above the transverse slot 22, is divided intermediate its ends by means of a diagonally extending slit 24, into a pair of yieldable spring fingers 25 and 26, the spring finger 25 preferably 30 being of greater length than the spring finger 26. This feature is clearly illustrated in Figure 6. It is preferred, that the diagonally extending slit 24 extend outwardly from a point at the vertical or longitudinal center 35 of the body portion 12, and to that side of the longitudinal center of the body portion so that the longer spring finger 25 will be disposed to that side of the body portion to which the pointed free end of the spring 20 is disposed. Speaking more briefly, the slit 24 extends in a general direction toward the pointed end 21 of the tongue 20.

Referring to the attachment of the holder to the vamp of the pump, it will be seen 40 that the base portion 13 merely engages the under side of the vamp and thus eliminates any possibility of defacing the upper or exposed faces of the vamp which would be undesirable when the pump was being worn without an ornamental buckle of any character. It will be apparent that when the fangs 16 are drawn into biting engagement with the inner side of the vamp 18, that the holder will be effectively held in posi-

tion by the fangs. It will also be apparent 65 that the holder may be readily placed in position after a person's foot has been placed in the pump, by merely sliding the base portion between the under side of the vamp and the person's instep, and when slid into such 70 position, the fangs 16 will prevent withdrawal of the holder from its adjusted position. When the holder is in position upon the pump, it will be seen that the vamp will not press or cut the instep due to the saddle 75 like formation of the base portion which tends to relieve all pressure or binding on the instep.

In locking the buckle upon the holder B, and which locking relation may be performed either before or after the holder has been applied to the shoe, the buckle is slid transversely of the holder with the cross bar 11 passing beneath the spring tongue 20 and in contact with the forward face of the upstanding body portion 12 as illustrated in the dotted line showing marked "X" in Figure 6. The longer spring finger 25 may then be forced rearwardly for allowing the cross bar 11 to pass behind the pointed end of the shorter spring finger 26. The buckle may then be swung to a position as indicated by the dotted line showing marked Y in Figure 6, and which will allow the spring finger 25 to assume its normal position with respect to the spring finger 26. The buckle may then be swung back until the cross bar 11 assumes a vertical position at the center of the body portion 12. Thus it will be seen that the spring tongue 20, spring fingers 25 and 26, and the medial web or rib 23, creates a binding action upon the cross bar 11 for holding the buckle firm and straight on the pump. By so having the slit 24 extend diagonally as illustrated, such aids in the 105 positioning of the cross bar beneath the spring fingers, and also causes the cross bar to bear against the free ends of both of the spring fingers when the buckle is in its adjusted position.

From the foregoing description it will be apparent that an extremely simple and effective holder for the supporting of buckles or other ornaments upon the vamp of a pump has been provided which will allow 115 various ornaments or buckles of varying descriptions to be detachably secured to the vamp without liability of defacing the vamp.

Various changes may be made to the specific form of invention herein shown and described, without departing from the spirit of the invention or the scope of the following claims.

I claim:

1. A holder of the class described comprising a base portion having rearwardly inclined fangs struck upwardly therefrom

for biting engagement with the underside of the vamp of a pump or the like upon slight upward and rearward slipping of the base portion, and an upstanding body portion for 5 the supporting of an ornament.

2. A buckle holder comprising a base portion and an upstanding body portion, said body portion provided with a transversely extending tongue, a medial rib lying flush 10 with the body portion, and transversely extending spring fingers in spaced relation above said rib and normally lying flush with the body portion, said spring fingers meeting at their inner free ends and divided at 15 their inner abutting ends by a diagonally extending slit extending in a general direction toward the free end of the spring tongue.

3. A buckle holder comprising a base portion and an upstanding body portion, said body portion having a forwardly struck tongue adjacent its lower portion extending transversely of the vertical center of the body portion, a transverse rib above said 20 tongue, and provided with an aperture above said rib, transversely extending fin-

gers closing the upper end of said aperture and divided above said aperture by a diagonally extending slit extending upwardly from the vertical center of the body portion 30 and extending in a direction toward the free end of said tongue, said tongue and fingers adapted to releasably engage the vertical cross bar of a buckle for detachably supporting the same upon the holder. 35

4. A buckle holder comprising a base portion and an upstanding body portion, said body portion having a transverse web and provided with an aperture above said web, a tongue joined at one end to the body portion and extending transversely of the vertical center of the body portion below said web, and spring fingers one of greater 40 length than the other, closing the upper end of said aperture and having diagonally extending free end portions disposed in abutting relation above said aperture, and with said longer finger disposed to that side of the body portion at which the free end of the tongue is disposed. 45

WALTER THOMAS MOON.
